DESIGN FOR A CAN

Earl M. Nielsen, Point Loma, Calif.

Application May 13, 1933. Serial No. 48,107

Term of patent 14 years

To all whom it may concern:

Be it known that I, EARL M. NIELSEN, a citizen of the United States of America, residing at Point Loma, in the county of San Diego and State of California, have invented a certain new, original, and ornamental Design for a Can, of which the following is a specification; reference being had to the accompanying drawing forming a part thereof.

Figure 1 is a perspective view of my new de-

sign for can; and Fig. 2 is a fragmentary sectional view thereof through 2—2 of Fig. 1.

I claim:

The ornamental design for a can, substantially as shown.

In testimony whereof, I have hereunto set my hand at San Diego, California this 8th day of May 1933.

EARL M. NIELSEN.
